UNITED STATES PATENT OFFICE.

JOHNSTON A. GREEN, OF SIGOURNEY, IOWA.

OIL BURNER.

Application filed March 13, 1924. Serial No. 699,019.

To all whom it may concern:

Be it known that I, JOHNSTON A. GREEN, a citizen of the United States, residing at Sigourney, in the county of Keokuk and 5 State of Iowa, have invented certain new and useful Improvements in Oil Burners, of which the following is a specification.

This invention relates to oil burners and more particularly to such a device especially 10 adapted for use in furnaces of the hot air type.

An important object of the invention is the provision of a device of the above mentioned character which is simple in construction and easily assembled within the usual type of hot air furnace without material alteration thereof.

A further object of the invention is to provide a simplified type of burner construction having novel means for supplying primary and secondary air to support combustion of the oil whereby complete combustion is effected.

Other objects and advantages of the invention will be apparent during the course 25 of the following description.

In the drawings I have shown one embodiment of the invention. In this showing, Figure 1 is a central vertical sectional 30 view,

Figure 2 is a section on line 2—2 of Figure 1,

Figure 3 is a section on line 3—3 of Figure 1, and,

Figure 4 is a sectional perspective view 35 of the secondary air tube supporting member.

Referring to the drawing the numeral 10 designates the outer shell or drum of an 40 ordinary hot air furnace shown in the present instance as the pipeless type. A second drum 11 is arranged concentrically within and spaced from the drum 10 to provide the usual cold air space 12. The upper 45 ends of the drums 10 and 11 are adapted to support the usual register 13. A third drum 14 is arranged concentrically within and spaced from the drum 11 to provide the usual hot air space 15 as will be understood.

50 The drum 14 terminates a substantial distance below the upper ends of the drums 10 and 11 and is closed by a plate 16 as shown in Figure 1. The interior of the drum 14 forms the usual fire box and a fire door 17 communicates with the fire box 55 through a tube 18 extending through the

drums 10, 11 and 14. A chimney connection 19 of the usual type is provided having a damper 20 arranged therein. As shown in Figure 1, the drums 10 and 14 are adapted 60 to rest upon a base 21 and the lower end of the drum 11 terminates a substantial distance above the base 21 to provide communication between the hot and cold air spaces 12 and 15. The drum 14 is provided 65 interiorly near its lower end with an internal annular flange 22 adapted to support a disk 23 forming a substantial closure for the lower end of the drum 14. The space between the disk 23 and base 21 provides an 70 air space 24 from which air is drawn to support combustion as will be described. Communication between the atmosphere and the space 24 is afforded through a tube 25 and passage of air into the space 24 may be 75 controlled by a door 26.

The numeral 27 designates a burner cup arranged within the fire box as clearly shown in Figure 1 and adapted to be supported upon the disk 23 by lugs 28. The 80 cup 27 is arranged concentrically within and spaced from the walls of the drum 14 and the space between the cup 27 and drum 14 is adapted to be filled with material 29, preferably asbestos. The bottom 30 of the 85 cup 27 is provided with a central apertured opening adapted to receive the threaded lower end of a primary air tube 31. The tube 31 is provided adjacent its lower end with a thickened annular portion 32 provided with a plurality of oil supply openings 33 threaded at their lower ends to receive the threaded upper ends of oil tubes 34. The oil tubes 34 are supplied with oil from a pipe 35 controlled by a valve 36 95 shown in Fig. 3. The space between the thickened lower end 32 of the tube 31 and the side walls of the cup 27 is preferably filled with absorbent material 37 which may be asbestos or any other desired material. 100

The disk 23 is centrally apertured as at 38 and a supporting member 39 is arranged within this opening. As shown in Figure 4 the supporting member 39 is provided at its upper end with an outstanding annular flange 40 provided with openings 41 adapted to receive bolts (not shown) by means of which the supporting member 39 may be secured against the lower end of the air tube 31. The supporting member 39 110 is provided with a closed bottom 42 which is connected to the flange 40 by side walls

43 apertured as at 44 for the passage of air as will be described. The supporting member 39 is provided centrally with an upwardly extending tubular portion 45 for a purpose to be described. The flange 40 is also apertured as at 46 and the oil pipes 34 extend through these apertures for connection with the openings 33.

Referring to Figures 1 and 3, the numeral 10 47 designates a supplementary air tube, the lower end of which is arranged within the tubular portion 45 of the supporting member 39. The tube 47 is provided near its lower end with an annular flange 48 15 adapted to rest upon the tubular portion 45 to be supported thereby. As shown in Figure 1, the tube 47 is arranged concentrically within the tube 31 and spaced therefrom to provide an air passage 49. An 20 air distributing member 50 is arranged on the upper end of the tube 47. The member 50 is hollow as shown in Figure 1 and communicates with the interior of the tube 47. The lower wall 51 of the member 50 is 25 apertured as at 52 to permit egress of air from the interior of the member 50.

The operation of the device is as follows:

The pipe 35 is connected to a suitable source of fuel oil supply and the valve 36 30 is opened to permit oil to flow through the pipes 34 to saturate the asbestos 37. The oil within the burner cup is ignited through the door 17 and after the oil has been burning a short time the cup 27 and tube 31 are 35 heated thus assisting in the vaporization of the oil. The draft created through the pipe 19 due to the combustion of the oil draws air upwardly through the openings 44 and 49 to supply primary air to support combustion of the oil. At the same 40 time secondary air is supplied through the openings 52 whereby complete combustion is effected. If the quantity of air supplied is excessive the draft may be regulated by 45 the damper 20. The rate at which the oil burns and consequently the intensity of the heat can be regulated by the valve 36 to permit the oil to flow at a faster or slower rate into the asbestos 37. When it is desired 50 to shut off the burner it is merely necessary to close the valve 36 and the oil held by the asbestos 37 will soon burn out and the flame be extinguished.

It will be apparent that the heating of 55 the fire box in the manner just described will heat the hot air space 15 causing the air therein to rise as will be obvious, the distributor 50 acting as a spreader to direct the flame outwardly against the wall 14 60 to assist in highly heating the space 15. As the air in space 15 rises it will be apparent that the air within the space 12 will move downwardly and be fed into the space 15 to be heated by the drum 14. Obviously 65 the heated air in the space 15 will flow

upwardly into the room above through the register 13. While I have shown the burner as applied to a hot air furnace of the pipeless type it will be obvious that the invention is not limited to the application shown 70 but may be applied with efficient results to any type of furnace.

It is to be understood that the form of my invention herewith shown and described is to be taken as a preferred example of the 75 same, and that various changes in the shape, size, and arrangement of parts may be resorted to without departing from the spirit of the invention or the scope of the subjoined claims.

Having described my invention, I claim:

1. A device of the character described comprising a burner cup having an open upper end, an air tube arranged concentrically within said cup and affording communication between the interior of said cup and the space therebelow, means for supplying fuel to said burner cup, and a secondary air tube arranged concentrically within the first 85 named air tube and adapted to discharge air above the upper end thereof adjacent the upper end of said burner cup.

2. A device of the character described comprising a burner cup having an open upper end, an air tube arranged concentrically within said cup and affording communication between the interior of said cup and the space therebelow, means for supplying fuel to said burner cup, a secondary air tube arranged concentrically within and spaced from the first named air tube, and an air distributor arranged on the upper end of said air tube, said distributor being provided with a discharge opening arranged adjacent the upper end of said burner cup.

3. A device of the character described comprising a burner cup provided in its bottom with a central opening, an air tube arranged in said burner cup over the opening therein, means for supplying fuel to said burner cup, a secondary air tube arranged concentrically within and spaced from said first named air tube, and a hollow circular air distributor arranged on the upper end of and communicating with said secondary air tube above the upper end of said first named air tube, said distributor being provided in its lower wall with a plurality of openings.

4. A device of the character described comprising a burner cup provided in its bottom with an axial opening, a primary air tube arranged concentrically within said burner cup over the opening therein, a body of absorbent material arranged in the bottom of said burner cup between the walls thereof and said air tube, said tube being provided with a thickened portion having an oil passage therein communicating at its upper end with the interior of said burner cup below the level of the absorbent mate-

rial therein, an oil supply pipe connected with the lower end of said passage, a secondary air tube arranged concentrically within and spaced from said primary air tube, 5 and a hollow circular air distributor arranged on the upper end of said secondary air tube a substantial distance above the upper end of said primary air tube, the lower wall of said distributor being provided with 10 a plurality of openings.

5. A device constructed in accordance with claim 4 wherein said secondary air tube is provided adjacent its lower end with an annular flange, and an apertured supporting 15 member arranged below said primary air tube, said supporting member being provided with a central tubular portion adapted to receive the lower end of said secondary air tube, said flange being adapted to rest on 20 the upper end of said tubular portion.

6. A device of the character described comprising a burner cup provided in its bottom with an axial opening, a primary air tube arranged, concentrically within said

burner cup over the opening therein, a body 25 of absorbent material arranged in the bottom of said burner cup between the walls thereof and said air tube, said tube being provided with a thickened bottom portion having an oil passage therein communicating at its upper end with the interior of said burner cup below the level of the absorbent material therein, an oil supply pipe communicating with the lower end of said passage, 30 a relatively flat hollow air distributing member arranged a substantial distance above the upper end of said primary air tube, the lower wall of said distributing member being provided with a plurality of openings, and means for supplying secondary air to 35 the interior of said distributing member.

In testimony whereof I affix my signature in presence of two witnesses.
